US00D866595S

(12) **United States Design Patent**
Sánchez Cascón et al.

(10) Patent No.: **US D866,595 S**
(45) Date of Patent: **** Nov. 12, 2019**

(54) **DISPLAY SCREEN WITH ICON**

(71) Applicant: **King.com Limited**, St. Julians (MT)

(72) Inventors: **Antonio Sánchez Cascón**, Barcelona (ES); **Julio López Cruz**, Barcelona (ES); **Maria Esther López Rodriguez**, Barcelona (ES); **Lidia Morales Estevez**, Barcelona (ES); **Oscar Gaya Belles**, Barcelona (ES)

(73) Assignee: **KING.COM LIMITED**, St. Julians (MT)

(**) Term: **15 Years**

(21) Appl. No.: **29/681,566**

(22) Filed: **Feb. 26, 2019**

Primary Examiner — Cathron C Brooks

Assistant Examiner — Andrew T Nemeth

(74) *Attorney, Agent, or Firm* — Arent Fox LLP

(57) **CLAIM**

The ornamental design for a display screen with icon, as shown and described.

DESCRIPTION

The design patent application file contains at least one drawing executed in color. Copies of this design patent application publication with color drawing(s) will be provided by the Office upon request and payment of the necessary fee.

The FIGURE is a front view of a display screen with icon showing our new design.

The broken line showing of the display screen and electronic device illustrate the article of manufacture and environmental structure, respectively, and form no part of the claimed design.
